(57) **CLAIM**

The ornamental design for a security bulwark for mounting along the perimeter of a vessel or marine installation, as shown and described.

DESCRIPTION

1. Security bulwark for mounting along the perimeter of a vessel or marine installation

1.1 is a perspective view of a security bulwark for mounting along the perimeter of a vessel or marine installation showing my new design;

1.2 is a front elevation view thereof;

1.3 is a left side elevation view thereof;

1.4 is a right side elevation view thereof;

1.5 is a rear elevation view thereof;

1.6 is a top plan view thereof; and,

1.7 is a bottom plan view thereof.
